CLAIM

The ornamental design for a console for surveillance system controller, as shown and described.

DESCRIPTION

FIG. 1 is a perspective view of a console for surveillance system controller showing our new design;

FIG. 2 is a top plan view thereof;

FIG. 3 is a bottom plan view thereof;

FIG. 4 is a right side elevational view thereof; and,

FIG. 5 is a back elevational view thereof.

The left side of the console for surveillance system controller is a mirror image of the right side displayed in FIG. 4. The portions shown in broken lines do not form any part of the claimed design.
